UNITED STATES PATENT OFFICE.

JOHN T. WALTER, OF EASTON, PENNSYLVANIA.

FEED-HOPPER.

SPECIFICATION forming part of Letters Patent No. 298,126, dated February 5, 1884.

Application filed May 10, 1883. (No model.)

To all whom it may concern:

Be it known that I, JOHN T. WALTER, of Easton, in the county of Northampton and State of Pennsylvania, have invented certain new and useful Improvements in Feed-Hoppers; and I do hereby declare that the following is a full, clear, and exact description thereof, reference being had to the accompanying drawings, and to the letters of reference 10 marked thereon, which form a part of this specification.

This invention relates to improvements in separating-feeders for middlings-purifiers. It relates more particularly to that class of preliminary separators in which a current of air is caused to pass through the middlings as they fall from a hopper, for the purpose of removing the larger and lighter impurities therefrom, which current is drawn into and 15 through a settling-chamber, wherein the larger particles removed from the middlings by it are deposited, the fine dust or fuzz being carried by said current from said chamber to a dust-room or elsewhere. Its object is to generally improve the construction of that class 20 of separating-feeders referred to; and it consists in the matters hereinafter described, and set forth in the claims.

The feeder embodying my invention is, for 30 convenience, illustrated in connection with a portion of the mechanism of a middlings-purifier invented by me, and for which an application for Letters Patent is now pending; but such feeder is equally applicable to any middlings-purifier of the same general construction 35 as the one mentioned; or it may be used as an independent separator, as will be hereinafter more fully explained.

In the accompanying drawings, Figure 1 is 40 a perspective view of a separating-feeder embodying my invention, such feeder being shown in connection with a portion of the top of a middlings-purifier and with an exhaust-fan thereon. Fig. 2 is a vertical transverse 45 section of the feeder mentioned, taken upon the line $x-x$ of Fig. 3. Fig. 3 is a front elevation of the same.

A is a portion of the upper part of the middlings-purifier having an inclined screen, A', placed in a suitable housing, and a space, A'', in the upper portion of such housing, which is

connected to the inlet-opening of an exhaust-fan, A'', (shown in Fig. 1,) placed upon the top of the machine, and with the compartment in which the said screen A' is placed by openings 55 in said compartment, which communicate by suitable passages (not shown) with the said space A'.

The parts of the middlings-purifier described are not necessary to the operation of 60 my invention, and the screen A' may be any screen upon which it is desired to feed the middlings or other material, and the space A'' may represent any passage communicating with the inlet-opening of an exhaust-fan. 65

B is the hopper of the feeder, which is supported above the head of the screen A', and C is a feed-roller placed at the exit-opening at the bottom of said hopper, and arranged to deliver the material therefrom in a thin stream 70 to the said screen, and which is constructed and operates in a well-known manner. The roller C is supported in suitable bearings upon the casing or housing of the feeder, and is given its rotary movement by means of a spur-wheel, 75 C', which meshes with a pinion, C'', placed upon a suitable driving-shaft, as shown.

Beneath the feed-roller C is a vertical passage, D, which is placed over the inlet-opening a in the top of the purifier proper, and 80 through which the middlings descends as it is fed from the hopper.

At one side of the passage D, and at the lower end thereof, is formed a narrow horizontal opening, D', and communicating with 85 the said passage at the opposite side thereof is an upwardly-extending passage, D'', which is connected to the settling-chamber E, said chamber communicating, by means of a vertical passage, F, and the space A'', with the 90 exhaust-fan A''. The opening D' and the passage D'' extend the full width of the passage D, and the current of air drawn by the exhaust-fan through said opening passes diagonally upward through the stream of middlings, 95 falling through the passage D and through the passage D'', carrying with it a considerable portion of the lighter and coarser impurities and dust contained in said middlings. After passing upwardly through the passage D'', such 100 air is drawn through a semicircular passage, d'', at the top of the feeder, and downwardly

into the settling-chamber E, which is provided with a vertical screen, e, constructed to effect a separation of the larger and heavier particles from the dust and fuzz contained in such air. From the chamber E the air-current, carrying with it the fine dust or fuzz, is drawn downwardly through the vertical passage F, and through an aperture, f, in its bottom into the space A², out of which it is taken by the exhaust-fan.

For the purpose of regulating the exit of the material from the hopper B as it is fed therefrom, a sliding-valve, I, is placed over the opening b, through which the material escapes from the hopper. The said valve is connected to and is operated by a horizontal disk or plate, G, placed in the interior of the hopper, and so arranged that when the material in the hopper is above the top of said plate it will be carried downwardly by the weight of the material thereon, and will move said slide-valve, through the medium of its connection therewith, so as to keep the exit-aperture open. A spring, i, is preferably arranged to act upon the valve I, which spring tends to keep the said valve closed, so that when the material in the hopper falls below the limit of the downward movement of the plate G its action upon said plate will cease, and the valve will be moved by said spring so as to reduce the exit-aperture until the material rises in the hopper and the plate is again drawn downward thereby. The plate G is attached to the end of a lever, G', which lever passes through the front wall of the hopper and is pivoted thereto. The outer arm of the said lever G' is connected, by means of a rod, g, with a short arm, h, upon a rock-shaft, H, which is mounted in bearings at the sides 40 of the feeder, and is arranged in a position parallel to and a short distance from the slide I. The arm h is placed upon the central portion of the rock-shaft, and upon said shaft, near both ends thereof, are also placed two arms, h', which are connected at their extremities to the slide I, so that when the inner end of the lever G' is depressed by the descent of the plate G, and the ends of the arms h and h' are drawn upward thereby, the said slide will be raised, and the 50 width of the aperture b increased. The arms h and h' are preferably attached to the rock-shaft H by means of short hubs or sleeves h², which encircle said shaft, and which are provided with set-screws h³, by which the said arms may be set at any desired angle. The 55 relative positions of the plate G and the slide I may thus be adjusted so as to vary the width of the exit-opening, as is found necessary or desirable in the operation of the feeder. The ends of the arms h' are preferably secured to the slide I by having their ends inserted in apertures in said slide; but any other convenient or preferred device for connecting the said arm to the slide may be used. The ends of the slide 60 I are supported in suitable guides, as shown. The spring i, for causing the slide I to remain closed, when the material in the hopper falls

below the top of the plate G, is preferably half-elliptical in form, and is secured to the hopper above said slide, with its ends resting 70 upon the upper edge thereof. The said spring is held at its central portion in an eye formed upon the end of an adjustable plate, I'. The said plate I' is slotted, and is held upon the front wall of the hopper by means of a thumb-nut, i', placed upon a bolt secured in said hopper, and passing through the slot in said plate, whereby the said spring may be adjusted to act upon the slide with greater or less pressure, as desired. The spring i is preferably 80 made of steel wire, and the upper edge of the slide I is provided with a longitudinal groove, in which its ends rest, and by which they are held in place. Any desired or preferred kind of spring or springs may be used to force the 85 slide I downward in place of the spring i described; or the valve may be weighted so as to accomplish the same object.

In order to limit the upward movement of the slide I, an adjustable stop, I², is placed 90 upon the front wall of the hopper above the said slide, and secured thereto by means of a thumb-screw, as shown. By adjusting said stop, the amount of vertical play permitted in the said slide and the size of the exit-aperture b may be varied, as desired, so that when there is a continuous discharge to the said hopper, through a spout from a bin or elsewhere, the exit-opening may be regulated to discharge the material as fast as it is received into the 100 hopper.

In order to effect a more perfect separation of the material passing into the chamber E with the air-blast, a vertical screen, e, is placed in the upper portion of said chamber, and between the inlet and outlet passages at the top thereof. This screen is made of the requisite fineness, to allow the passage of the fine dust or fuzz contained in the air, but to exclude the coarser particles which it is desired to separate therefrom, which coarser particles, being arrested by the said screen, fall to the bottom of the receptacle.

For the purpose of providing an additional separation of the fine dust from the coarser particles mentioned, a horizontal slit or opening, E', is formed in the exterior wall of the chamber E, through which opening a current of air is drawn, which current passes upwardly through the material arrested by the screen e, and falls to the bottom of the receptacle. The opening E' is provided with an adjustable slide-valve, e', by which the air-current may be regulated as is found necessary. The bottom of the receptacle E is provided with an inclined bottom, as shown, which bottom slopes toward an exit-opening, E², for the escape of the material deposited therein. A depending outwardly-opening flap-valve, e', is placed over the aperture E², which allows the outward passage of the material accumulated behind it, but prevents any inflow of air. A regulating-valve, f', is arranged to control the opening at the upper end of the passage

F, which forms the exit-opening for the air from the chamber E. The said valve is attached to a shaft, f^2 , which extends through the side of the feeder at one of its ends, and 5 is provided with a slotted segmental plate, f^3 , which may be secured so as to hold the valve f' in any desired position by means of a thumb-screw, f^4 , placed upon a bolt secured in the side of the feeder and extending through the 10 slot in said plate f^2 . By moving the valve f' the strength of the air-current passing through the feeder may be varied so as to produce the most effective result, and according to conditions in the material operated upon. As an 15 additional means of regulating the air-current, an aperture is formed in the side of the passage F, which aperture is provided with a pivoted valve, F'. By opening the valve F' air may enter the passage F and will pass directly 20 through the opening f to the exhaust-fan, and thus lessen, to a greater or less extent, the draft through the passages of the feeder.

For the purpose of providing a compact and 25 economical structure in the feeder, and in order to locate the chamber E in position to allow the convenient discharge of material therefrom and the entrance of air thereto, the air-passages D^2 and F are placed side by side, and 30 between the said chamber and the hopper B. The chamber E and the passage D^2 are connected by means of a passage, d^2 , formed between two semicircular plates, d^3 and d^4 , which project above the top of the hopper, as shown. 35 The passage d^2 opens into the top of the chamber E at one side of the screen e and adjacent to the outside wall of said chamber, the inner semicircular plate, d^4 , being connected at one end to the top of the said screen and at the 40 other end to the top of the partition d' , between the passages D^2 and F. The partition-wall e' between the chamber E and the passage F terminates at its top between the ends of the curved plate d^4 mentioned, so that the 45 air drawn from the said chamber passes over the upper edge of said partition and into said passage. The shaft f^2 of the valve f' is placed in contact with the said plate d^4 at its central portion, as shown in Fig. 2, and rotates in 50 contact therewith when moved, so as to prevent the passage of air around said valve and into the passage F upon its opposite side. The front wall, d , of the passage D is inclined forward, as shown, so as to deflect the material 55 passing from the hopper over the roller C into said passage, such construction being necessary on account of the size of the roller and the location of the other parts in the machine, as shown.

60 In order to prevent any upward passage of air through the aperture a , through which the material from the feeder described passes downwardly to the screen of the middlings-purifier, a narrow transversely-arranged receptacle, a' , is preferably placed in the puri-

fier and beneath the said aperture, which receptacle is provided in its bottom with a depending flap-valve, a' , constructed to allow the downward passage of the material falling into said receptacle, but which will close and prevent the upward passage of air toward the feeder. 70

The separating-feeder described need not necessarily be placed so as to feed directly into a middlings-purifier, but may be used separately, it being necessary in such case to connect it to a separate fan. The device described may also be used in the process of gradual reduction, for taking out the light bran from the material between the breaks. 75

I claim as my invention—

1. In a feeding-hopper, the combination, with a valve, I, for regulating the exit of material from the hopper, of a plate, G, located within the hopper, a pivoted lever, G', connected with the said plate, and a rock-shaft, H, provided with arms h and h' , connected, respectively, with said lever and valve, substantially as described. 85

2. In a feeding-hopper, the combination, with a valve, I, for regulating the exit of material from the hopper, of a plate, G, located within the hopper, a pivoted lever, G', connected with the said plate, a rock-shaft, H, and arms h and h' , adjustably secured to said 95 shaft and connected, respectively, with said lever and valve, substantially as described.

3. The combination, with a feed-hopper, B, of a sliding valve, I, a plate, G, located in the hopper, connections joining the plate G and the valve, a spring, i, constructed to engage the said valve at its ends, a plate, I', adjustably secured to the hopper and connected with the said spring at the central portion of the latter, and an adjustable stop, I², for limiting 105 the upward movement of the valve, substantially as described.

4. The combination, with an exhaust-fan, of a hopper, B, provided with a passage, D, a settling-chamber, E, located in the same casing as the said hopper and adjacent thereto, a screen, e, located in the upper portion of said chamber, and a partition, d' , located between the adjacent walls of the hopper and chamber, and joined at its ends to the side walls of the 110 casing, and constructed to form with said walls of the hopper and chamber passages D^2 and F, connecting the top of the chamber at opposite sides of the screen e with the passage D and with the said exhaust-fan, substantially as described. 115

In testimony that I claim the foregoing as my invention I affix my signature in presence of two witnesses.

JOHN T. WALTER.
